10 Claims. (Cl. 315—101)

This invention relates to a starting and operating device for gaseous electric discharge lamps, more particularly to fluorescent lamps, in the bridge circuit of the preheatable incandescent electrodes of which a glow switch is connected in series with a thermostatic switch. Well known designs of connecting in series a glow switch with a thermostatic switch do, up to the present, not offer a suitable starting and operating device for electric discharge lamps because the following drawbacks have been found in the design of both the aforesaid switching elements. The glow switch used hitherto makes already, as it is known from the usual glow switch starter, several contact closures at closing and causes thereby several voltage impulses which, however, do not start the lamp but which impair its electrodes. Sometimes it happens that the glow switch remains in a closed position beyond the opening time of the thermostatic switch so that the fluorescent lamp extinguishes shortly after having started. Such and other faults have, hitherto, hindered the use of combined thermostatic and glow switches connected in series in practice.

The aforesaid drawbacks are, according to the present invention, prevented in starting and operating devices of the above kind in such a manner that the glow switch is designed for an impulse voltage which is lower than that voltage required for starting the arc discharge in a fluorescent lamp with cold electrodes to be started whereas the thermostatic switch brings about an impulse voltage above the starting voltage of a fluorescent lamp with preheatable electrodes. By rating the glow switch in the aforesaid manner it is prevented that voltage impulses caused already by bad contact making when the glow switch is closed are brought about in the connected fluorescent lamp which voltage impulses have, as it is well known, a very bad influence upon electrodes when they are still cold.

To obtain a perfect operation of the combined starter according to the present invention it is, furthermore, suitable to design the glow switch for the special characteristics of a short closing time, a sufficient contact-point pressure and particularly a low impulse voltage of preferably about 400 volts and to design the thermostatic switch for a high opening speed, a higher impulse voltage and a slow cooling. Consequently, the bimetallic strip of the glow switch has a thickness of preferably 0.2 mm. or less and a length of preferably 14 mm. or less and a filling pressure of Ne or A with small additions of H₂ or N₂ amounting preferably to more than 40 mm. Hg whereas the bimetallic strip of the thermostatic switch has a greater or at least the same thickness and a smaller or at most the same thickness and a smaller or at most the same length as the bimetallic strip of the glow switch and is filled with Ne with smaller additions of H₂ or N₂ of preferably 10 mm. Hg or less. A very favorable rating of the starting switches consists in providing the glow switch with a bimetallic strip of about 0.08-2.5-12 mm. and a gas filling of neon+10% H₂ at a filling pressure of about 65 mm. Hg whereas the thermostatic

2

switch has a bimetallic strip of about 0.12-3-12 mm. and approximately the same gas filling as the glow switch at a filling pressure of about 2 mm. Hg. If both the switching elements are rated in such a different manner it is obtained that the glow switch closes its contact in the shortest possible time after applying the line voltage. By means of the high filling pressure of the glow switch of more than 40 mm. Hg together with the symmetrical construction of its electrodes it is obtained that even in case of a bad contact a sufficient impulse voltage for starting the discharge lamp is not produced at that moment at which the glow switch closes, at which moment the electrodes are still cold. In case of usual fluorescent lamps of 40 watts and a length of 1.20 m. the voltage required for starting the arc discharge with cold electrodes lies for instance above 500 volts. If the glow switch is rated in the above mentioned manner it produces only an impulse voltage of about 400 volts so that undesired cold startings of the discharge lamp are prevented with safety. That's particularly the case because the energy of the voltage impulse of the glow switch is very low in the present case because of the short opening time and remains without any remarkable effect upon the lamp.

25 The heating coil of the thermostatic switch has, suitably, the same heating speed as the electrode coils of the discharge lamp so that the contact of the thermostatic switch is opened when the electrode coil has obtained the proper emission temperature. Suitably, the heating coil 30 of the thermostatic switch has the same characteristics with regard to material, diameter and pitch as the electrode coils of the discharge lamp. They may be cut from the same coil and differ only in their lengths.

After the glow switch contact has closed the bimetal 35 of the thermostatic switch is heated quickly by means of the high capacity of the heating coil which is, suitably, twice as high as the heating capacity of the glow switch coil so that opening of the contact occurs with a great opening speed. The filling pressure of the filling 40 gas in the thermostatic switch is low according to the present invention so that a high impulse voltage occurs when the thermostatic switch contact is opened which impulse voltage starts the lamp with great safety. By means of the higher heating capacity of the heating coil 45 of the thermostatic switch its bimetal has taken up a greater quantity of heat than the bimetallic strip of the glow switch. By this means the thermostatic switch contact returns slower into the closed position of rest than the glow switch contact returns into the opened position.

50 In order to obtain a very low impulse voltage when the glow switch opens and a very high impulse voltage when the thermostatic switch opens the additional heating source of the glow switch should be connected to the counter contact of the bimetallic strip and the heating source of the thermostatic switch to the bimetallic strip itself. It is obtained thereby that in the glow switch the electrode surfaces have the same dimensions on both the sides of the contacts and bring about low impulse voltages whereas the thermostatic switch operating at 55 the moment of contact-opening similar to a glow switch starter in a gaseous atmosphere makes occur high impulse voltages in consequence of the rectifier effect happening in because of the dissymmetry of the electrode surfaces. By this means there are obtained at the same time in the glow switch definite distances of the glow paths because the unmovable part of the bimetallic strip forms the one electrode and the coil holders form the other glow electrode which are arranged in a constant distance from each other. A radio interference suppression capacitor causes in normal glow switches a slight 60 welding of the contacts whereby the time of closing, and, therewith, preheating of the electrode coils is prolonged,

be it not very exact. In combined starters of a thermostatic and glow switch this welding is not desirable because thereby the time of closing cannot be rated with safety. In view of these facts it is suitable to connect in series with the suppression capacitor a resistor of 100 to 1000 ohms, preferably of about 500 ohms. By this means the discharge current impulse of the condenser across the contacts of the glow switch is so weakened that a welding does no more occur. Preferably, the glow switch and the thermostatic switch, if desired together with the suppression capacitor bridging the starters and the damping resistor, are placed in a common protective casing thus permitting an easy insertion or a quick exchange of the double starter as in case of the well known simple glow switch starter. A further improvement in starting a discharge lamp operated in the aforesaid way may be obtained in such a manner that the lamp is provided with an igniting strip extending over nearly the whole length of the lamp, suitably connected to an electrode across a resistor. Finally, the starting and operating device as described in the present invention may be also operated in a bridge connection in which the incandescent electrodes of the lamp are connected across a choke coil and perhaps a condenser to the line voltage in such a manner that there is provided in the bridge circuit containing the glow switch and the thermostatic switch an additional counter-winding coupled with the choke coil in such a manner that this counter-winding diminishes the apparent resistance of the whole preheating circuit. By means of this well known arrangement of a counter winding coupled with the choke coil the preheating current of the lamp electrodes is much increased and the time of starting is shortened, i.e. starting of the lamp is guaranteed also in very cold weather.

In this latter case it is suitable to construct the starter as a safety starter, i.e. to build-in a further contact which interrupts the bridge circuit if the starter operates for a longer time, perhaps for 10 sec., for instance if the lamp is impaired or is not in operating conditions, which safety starter may, afterwards, be closed by hand. The choke coil may also be provided with a thermostitch which interrupts the whole circuit if the overcurrent continues and prevents thereby an injury to the choke coil by the high current brought about when the starter is closed.

If there are used choke coils with counter-winding the current intensity during the heating period may be increased by an appropriate rating of the counter winding to such a degree that the electrode obtains within fractions of a second that temperature which is required for starting. In such a case that time in which the glow switch remains in a closed condition also without additional heating suffices for the starting process so that no special heating of the bimetal of the glow switch is necessary.

One embodiment of the aforesaid starting and operating device according to the present invention is shown in the accompanying drawing. Fig. 1 is a schematic diagram of the starting and operating circuit employing the device of the invention with a sectional view in elevation of the glow switch and the thermostatic switch. Fig. 2 is a perspective view of this device. Fig. 1 shows a discharge lamp to be started, more particularly a low-pressure fluorescent lamp, with luminescent coating 2 and preheatable electrodes 3 connected in series across a bridge circuit 4. Furthermore, there lie in this bridge circuit 4 a glow switch 5 with a resistance heating wire 6 and a thermostatic switch 9 with a heating resistor 10. The contacts of both the starting switches 5 and 9 are bridged by a suppression capacitor 12 of about 5000 to 10,000 picofarads to which, if desired, a damping resistor 19 is connected in series. A series choke coil 13 serves, as it is well known, to limit the discharge current of lamp 1. If necessary, there is also provided a condenser 20 connected in series with one of the choking windings in order to obtain a capacitive reactance. Fur-

thermore, there is provided in the bridge circuit an additional winding 14 coupled inductively with the choke coil 17. As long as the main switch 15 is open the contact of the glow switch 5 is open whereas the contact of the thermostatic switch 9 is closed. After closing the main switch 15 the contact of glow switch 5 is, as it is well known, closed due to the heat of the glow discharge. Thereupon the resistance heating wire 6 goes on heating the bimetallic strip of glow switch 5 so that the glow switch remains in a closed condition as long as the bimetallic contact of the thermostatic switch 9 will be opened by the effect of its heating coil 10. By this continuous heating of glow switch 5 after the bimetallic contact has closed there is, consequently, obtained a longer preheating of the incandescent electrodes 3. As to the dimensions of the starters the following values have proved favourable which guarantee an exact operation of the starters. The bimetallic strip of the glow switch 5 has, in our example, a cross section of 0.08·2.5 mm. and a length of 12 mm. The bimetallic strip of the thermostatic switch 9 has the following dimensions: 0.12·3·12 mm. For both the switches there has been taken a neon-filling with an addition of about 10% of hydrogen. This gas-filling has a pressure of about 2 mm. Hg in case of the thermostatic switch and of about 65 mm. Hg in case of the glow switch. The heating resistors of the thermostatic switch and of the glow switch are rated in a proportion of about 2:1 up to 3:1, that means the thermostatic switch has about 5 turns of a coiled coil whereas the glow switch has only two turns with equal dimensions in all the other respects. Of course, it is quite possible to match the starters to each other correspondingly by taking other dimensions for the bimetallics, the heating coil and the gas pressure so that the aforesaid operation of the starters is guaranteed too.

To facilitate breaking of the easy welding contacts of the glow switch these contacts are made of molybdenum or a semi-conductor. One contact may also consist of molybdenum and the other of a semi-conductor. The heating element may consist also of a semi-conductor material with weak-negative temperature coefficient. In both these cases it will be caused that the bimetal 8 of the glow switch is again heated immediately after its contacts have closed by means of the additional heating element 6 and is kept closed thereby. In our example there is, for the purpose of a symmetrical distribution of the starter parts at both the sides of the contacts and, thereby, for the purpose of decreasing the impulse voltage, the additional heating source 6 of the glow switch 5 connected to the counter-contact 7 of the bimetallic strip 8. Vice versa, the heating element 10 of the thermostatic switch 9 is connected to the bimetallic strip 11 for the purpose of an asymmetrical arrangement of the starter parts at both the sides of the contacts and, thereby, for the purpose of supporting a higher impulse voltage.

A further improvement of preheating can, according to the present invention, be obtained in such a manner that the preheating current of the lamp electrodes 3 is increased by using the additional winding 14. If the starting device contains only a choke coil 13 then the additional winding 14 must be wound in a counter-clockwise direction to the choke winding so that the inductance of both the windings is decreased. If the starting device contains still a capacity 20 connected in series with the choke coil 13 then the additional winding 14 must be wound in a clockwise direction to the choke coil 13 so that in that case the inductance of the choke coil is increased by the preheating current. In both the above cases the apparent resistance of the whole preheating circuit must be decreased by the additional winding 14. After the thermostatic switch 9 has opened the contact and has started the lamp 1 then the contact of the glow switch 5 opens also again and the contact of the thermostatic switch starter returns into the contact position.

Now, as it is well known, the lamp voltage does not suffice to cause the glow switch 5 to operate.

Fig. 2 shows the assembly of the glow switch 5, of the thermostatic switch 9, of the radio interference suppression capacitor 12 and of the damping resistor 19 on a common base plate 16 which all are covered by a common protective casing 17. Thereby the combined starter is assembled to a unity and is dimensioned in such a manner that it may be inserted into the same place and into the same sockets as the glow switch starters used hitherto. In our example shown in the drawing the lamp 1 is, furthermore, provided with an igniting strip 18 which is connected electrically to one of the incandescent electrodes 3. By means of this arrangement a further improvement of the starting is obtained as far as such an improvement should be required at low temperatures. The igniting strip 18 may be provided in a well known manner outside or inside the lamp bulb. Thus by means of the above described and represented starting and operating device according to the present invention a sufficient, prolonged preheating of the lamp electrodes with an increased preheating current is obtained so that a quick and flickering-free starting takes place in a reliable manner even at low temperature.

What we claim as new and desire to secure by Letters Patent of the United States is:

1. A device for starting and operating a gaseous electric discharge lamp, more particularly of the fluorescent type, with two filamentary electrodes, comprising a glow switch and a thermostatic switch connected in electrical series relation with each other and with said filamentary electrodes forming a heating circuit for said filamentary electrodes, said glow switch having normally separated contacts and being operable to close the heating circuit for said filamentary electrodes upon application of a potential thereto, said glow switch being designed to remain closed under the action of the current flow through said heating circuit, said thermostatic switch having normally closed contacts operable to open following operation of said glow switch and to interrupt said heating circuit for said filamentary electrodes causing a high transient voltage above the voltage necessary for initiating a discharge in said lamp, said glow switch being so constructed and dimensioned to secure the transient voltage, caused by opening said glow switch contacts and thereby interrupting said heating circuit to be so low that initiating of a discharge between the cold electrodes in said lamp is prevented in a reliable manner.

2. A device for starting and operating a gaseous electric discharge lamp, more particularly of the fluorescent type, with two filamentary electrodes, comprising a glow switch and a thermostatic switch connected in electrical series relation with each other and with said filamentary electrodes forming a heating circuit for said filamentary electrodes, said glow switch having a gaseous medium of neon with small additions of hydrogen therein, the filling pressure of which is more than 40 mm. Hg and normally separated contacts, at least one of said contacts being a bimetallic strip of 0.2 mm. maximum thickness and 14 mm. maximum length which deflects into engagement with sufficient contact point pressure with the other of said contacts upon heating by the initially occurred glow discharge, thereby extinguishing the glow discharge and closing the heating circuit for said filamentary electrodes, said glow switch being designed to remain closed under the action of the current flow through said heating circuit, said glow switch securing by its structure and dimensioning the transient voltage, caused by opening said glow switch contacts in case of bad contacting and thereby interrupting said heating circuit, to be so low as approximately 400 volts that initiating of a discharge between the cold electrodes in said lamp is prevented with guaranty, said thermostatic switch having a gaseous medium of neon with small additions of hydrogen therein, the filling pressure of which is 10

mm. Hg at the most, and being provided with a heater element and having normally closed contacts to complete the heating circuit for said filamentary electrodes, at least one of said contacts being a bimetallic strip the minimum thickness and the maximum length of which is like said bimetallic strip of said glow switch said thermostatic switch opens contacts with high opening speed upon heating by said heater element after closing of the glow switch contacts, thereby interrupting said heating circuit for said filamentary electrodes causing a high transient voltage above the voltage necessary for initiating a discharge in said lamp.

3. A device for starting and operating a gaseous electric discharge lamp, more particularly of the fluorescent type, with two filamentary electrodes, comprising a glow switch and a thermostatic switch connected in electrical series relation with each other and with said filamentary electrodes forming a heating circuit for said filamentary electrodes, said glow switch having a gaseous medium of neon with an addition of 10% hydrogen therein, the filling pressure of which is approximately 65 mm. Hg, and normally separated contacts, at least one of said contacts being a bimetallic strip of 0.08 mm. thickness and 2.5 mm. width and 12 mm. length which deflects into engagement with sufficient contact point pressure with the other of said contacts upon heating by the initially occurred glow discharge, thereby extinguishing the glow discharge and closing the heating circuit for said filamentary electrodes, said glow switch being designed to remain closed under the action of the current flow through said heating circuit, said glow switch securing by its structure and dimensioning the transient voltage, caused by opening said glow switch contacts in case of bad contacting and thereby interrupting said heating circuit, to be so low that initiating of a discharge between the cold electrodes in said lamp is prevented with guaranty, said thermostatic switch having a gaseous medium of neon with an addition of 10% hydrogen therein, the filling pressure of which is approximately 2 mm. Hg, and being provided with a heater element and having normally closed contacts to complete the heating circuit for said filamentary electrodes, at least one of said contacts being a bimetallic strip of 0.12 mm. thickness and 3 mm. width and 12 mm. length said thermostatic switch opens contacts upon heating by said heater element after closing of the glow switch contacts, thereby interrupting said heating circuit for said filamentary electrode causing a high transient voltage above the voltage necessary for initiating a discharge in said lamp.

4. A device for starting and operating a gaseous electric discharge lamp, more particularly of the fluorescent type, with two filamentary electrodes, comprising a glow switch and a thermostatic switch connected in electrical series relation with each other and with said filamentary electrodes forming a heating circuit for said filamentary electrodes, said glow switch having a gaseous medium of neon with small additions of hydrogen therein, the filling pressure of which is more than 40 mm. Hg, and normally separated contacts, at least one of said contacts being a bimetallic strip of 0.2 mm. maximum thickness and 14 mm. maximum length which deflects into engagement with sufficient contact point pressure with the other of said contacts upon heating by the initially occurred glow discharge, thereby extinguishing the glow discharge and closing the heating circuit for said filamentary electrodes, said glow switch being designed to remain closed under the action of the current flow through said heating circuit, said glow switch securing by its structure and dimensioning the transient voltage, caused by opening said glow switch contacts in case of bad contacting and thereby interrupting said heating circuit, to be so low as approximately 400 volts that initiating of a discharge between the cold electrodes in said lamp is prevented with guaranty, said thermostatic switch having a gaseous medium of neon with small additions of hydrogen therein, the filling pressure of which is 10 mm. Hg at

the most, and being provided with a coiled heating filament of the same material and the same dimensions as to diameter and pitch as said coiled filamentary electrodes, differing at the most in its length from that of said filamentary electrodes, said thermostatic switch having normally closed contacts to complete the heating circuit for said filamentary electrodes, at least one of said contacts being a bimetallic strip the minimum thickness and the maximum length of which is like said bimetallic strip of said glow switch, said thermostatic switch opens contacts with high opening speed upon heating by said heater element after closing of the glow switch contacts, thereby interrupting said heating circuit for said filamentary electrodes causing a high transient voltage above the voltage necessary for initiating a discharge in said lamp.

5. A device for starting and operating a gaseous electric discharge lamp, more particularly of the fluorescent type, with two filamentary electrodes, comprising a glow switch and a thermostatic switch connected in electrical series relation with each other and with said filamentary electrodes forming a heating circuit for said filamentary electrodes, said glow switch having normally separated contacts, at least one of said contacts being a bimetallic strip of 0.2 mm. maximum thickness and 14 mm. maximum length which deflects into engagement with sufficient contact point pressure with the other of said contacts upon heating by the initially occurred glow discharge, thereby extinguishing the glow discharge and closing the heating circuit for said filamentary electrodes, said glow switch being provided with a heater element connected in electrical series relation with said contacts and maintaining said bimetallic element under the action of the current flow through said heating circuit in a heated condition and keeping said contacts closed, said glow switch securing by its structure and dimensioning the transient voltage, caused by opening said glow switch contacts in case of bad contacting and thereby interrupting said heating circuit, to be so low that initiating of a discharge between the cold electrodes in said lamp is prevented with guaranty, said thermostatic switch being provided with a heater element and having normally closed contacts to complete the heating circuit for said filamentary electrodes, at least one of said contacts being a bimetallic element which opens contacts upon heating by said heater element after closing of the glow switch contacts, thereby interrupting said heating circuit for said filamentary electrodes causing a high transient voltage above the voltage necessary for initiating a discharge in said lamp.

6. A device for starting and operating a gaseous electric discharge lamp, more particularly of the fluorescent type, with two filamentary electrodes, comprising a glow switch and a thermostatic switch connected in electrical series relation with each other and with said filamentary electrodes forming a heating circuit for said filamentary electrodes, said glow switch having a gaseous medium of neon with small additions of hydrogen therein, the filling pressure of which is more than 40 mm. Hg, and normally separated contacts, at least one of said contacts being a bimetallic strip of 0.2 mm. maximum thickness and 14 mm. maximum length which deflects into engagement with sufficient contact point pressure with the other of said contacts upon heating by the initially occurred glow discharge, thereby extinguishing the glow discharge and closing the heating circuit for said filamentary electrodes, said glow switch being provided with a heater element connected in electrical series relation with said contacts and maintaining said bimetallic element under the action of the current flow through said heating circuit in a heated condition and keeping said contacts closed, said glow switch securing by its structure and dimensioning the transient voltage, caused by opening said glow switch contacts in case of bad contacting and thereby interrupting said heating circuit, to be so low as approximately 400 volts, that initiating of a discharge between the cold electrodes in said lamp is prevented with guaranty, said ther-

mostatic switch having a gaseous medium of neon with small additions of hydrogen therein, the filling pressure of which is 10 mm. Hg at the most, and being provided with a heater element capable of at least twice the capacity loading of that of said glow switch heater element at the same current intensity, said thermostatic switch having normally closed contacts to complete the heating circuit for said filamentary electrodes, at least one of said contacts being a bimetallic strip the minimum thickness and the maximum length of which is like said bimetallic strip of said glow switch, said thermostatic switch opens contacts with high opening speed upon heating by said heater element after closing the glow switch contacts, thereby interrupting said heating circuit for said filamentary electrodes causing a high transient voltage above the voltage necessary for initiating a discharge in said lamp.

7. A device for starting and operating a gaseous electric discharge lamp, more particularly of the fluorescent type, with two filamentary electrodes, comprising a glow switch and a thermostatic switch connected in electrical series relation with each other and with said filamentary electrodes forming a heating circuit for said filamentary electrodes, said glow switch having normally separated contacts, at least one of said contacts being a bimetallic strip of 0.2 mm. maximum thickness and 14 mm. maximum length which deflects into engagement with sufficient contact point pressure with the other of said contacts upon heating by the initially occurred glow discharge thereby extinguishing the glow discharge and closing the heating circuit for said filamentary electrodes, said glow switch being provided with a heater element connected in electrical series relation with the counter contact of said bimetallic element and maintaining said bimetallic element under the action of the current flow through said heating circuit in a heated condition and keeping said contacts closed, said glow switch securing by its structure and dimensioning the transient voltage, caused by opening said glow switch contacts in case of bad contacting and thereby interrupting said heating circuit, to be so low as approximately 400 volts that initiating of a discharge between the cold electrodes in said lamp is prevented with guaranty, said thermostatic switch being provided with a heater element and having normally closed contacts to complete the heating circuit for said filamentary electrodes, at least one of said contacts being a bimetallic element connected in electrical series relation with said heater element, said thermostatic switch opens contacts upon heating by said heater element after closing of the glow switch contacts, thereby interrupting said heating circuit for said filamentary electrodes causing a high transient voltage above the voltage necessary for initiating a discharge in said lamp.

8. A device for starting and operating a gaseous electric discharge lamp, more particularly of the fluorescent type, with two filamentary electrodes, comprising a glow switch and a thermostatic switch connected in electrical series relation with each other and with said filamentary electrodes forming a heating circuit for said filamentary electrodes, and an ohmic resistance and a radio interference suppression capacitor connected in electrical series relation with each other and connected in parallel to said two switches, said ohmic resistance amounting to approximately 500 ohms, said glow switch having normally separated contacts, at least one of said contacts being a bimetallic strip of 0.2 mm. maximum thickness and 14 mm. maximum length which deflects into engagement with sufficient contact point pressure with the other of said contacts upon heating by the initially occurred glow discharge, thereby extinguishing the glow discharge and closing the heating circuit for said filamentary electrodes, said glow switch being designed to remain closed under the action of the current flow through said heating circuit, said glow switch securing by its structure and dimensioning the transient voltage, caused by opening said glow switch contacts in case of bad contacting and thereby

interrupting said heating circuit, to be so low as approximately 400 volts, that initiating of a discharge between the cold electrodes in said lamp is prevented with guaranty, said thermostatic switch being provided with a heater element and having normally closed contacts to complete the heating circuit for said filamentary electrodes, at least one of said contacts being a bimetallic element, said thermostatic switch opens contacts upon heating by said heater element after closing of the glow switch contacts, thereby interrupting said heating circuit for said filamentary electrodes causing a high transient voltage above the voltage necessary for initiating a discharge in said lamp.

9. A device for starting and operating a gaseous electric discharge lamp, more particularly of the fluorescent type, with two filamentary electrodes, comprising a glow switch and a thermostatic switch connected in electrical series relation with each other and with said filamentary electrodes forming a heating circuit for said filamentary electrodes, and an ohmic resistance and a radio interference suppression capacitor connected in electrical series relation with each other and connected in parallel to said glow switch, said ohmic resistance amounting to approximately 500 ohms, said glow switch having normally separated contacts, at least one of said contacts being a bimetallic strip of 0.2 mm. maximum thickness and 14 mm. maximum length which deflects into engagement with sufficient contact point pressure with the other of said contacts upon heating by the initially occurred glow discharge, thereby extinguishing the glow discharge and closing the heating circuit for said filamentary electrodes, said glow switch being designed to remain closed under the action of the current flow through said heating circuit, said glow switch securing by its structure and dimensioning the transient voltage, caused by opening said glow switch contacts in case of bad contacting and thereby interrupting said heating circuit, to be so low as approximately 400 volts, that initiating of a discharge between the cold electrodes in said lamp is prevented with guaranty, said thermostatic switch being provided with a heater element and having normally closed contacts to complete the heating circuit for said filamentary electrodes, at least one of said contacts being a bimetallic element, said thermostatic switch opens contacts upon heating by said heater element after closing of the glow switch contacts, thereby interrupting said heating circuit for said filamentary electrodes causing a high transient voltage above

the voltage necessary for initiating a discharge in said lamp.

10. A device for starting and operating a gaseous electric discharge lamp, more particularly of the fluorescent type, with two filamentary electrodes, comprising a glow switch and a thermostatic switch connected in electrical series relation with each other and with said filamentary electrodes forming a heating circuit for said filamentary electrodes, said glow switch having a gaseous medium of argon with small additions of hydrogen therein, the filling pressure of which is more than 40 mm. Hg and normally separated contacts, at least one of said contacts being a bimetallic strip of 0.2 mm. maximum thickness and 14 mm. maximum length which deflects into engagement with sufficient contact point pressure with the other of said contacts upon heating by the initially occurred glow discharge, thereby extinguishing the glow discharge and closing the heating circuit for said filamentary electrodes, said glow switch being designed to remain closed under the action of the current flow through said heating circuit, said glow switch securing by its structure and dimensioning the transient voltage, caused by opening said glow switch contacts in case of bad contacting and thereby interrupting said heating circuit, to be so low as approximately 400 volts that initiating of a discharge between the cold electrodes in said lamp is prevented with guaranty, said thermostatic switch having a gaseous medium of neon with small additions of hydrogen therein, the filling pressure of which is 10 mm. Hg at the most, and being provided with a heater element and having normally closed contacts to complete the heating circuit for said filamentary electrodes, at least one of said contacts being a bimetallic strip the minimum thickness and the maximum length of which is like said bimetallic strip of said glow switch, said thermostatic switch opens contacts with high opening speed upon heating by said heater element after closing of the glow switch contacts, thereby interrupting said heating circuit for said filamentary electrodes causing a high transient voltage above the voltage necessary for initiating a discharge in said lamp.
